UNITED STATES PATENT OFFICE.

JESSE G. ROSEBOOM, OF CINCINNATI, OHIO.

SIGNAL FOR MOTOR-VEHICLES.

1,353,361.

Specification of Letters Patent. Patented Sept. 21, 1920.

Application filed November 25, 1919. Serial No. 340,498.

To all whom it may concern:

Be it known that I, JESSE G. ROSEBOOM, a citizen of the United States, residing at Cincinnati, in the county of Hamilton and State of Ohio, have invented new and useful Improvements in Signals for Motor-Vehicles, of which the following is a specification.

My present invention pertains to vehicle signals and it contemplates the provision of a vehicle signal that may be readily secured to a vehicle and easily operated to indicate the direction in which the occupant or occupants of the vehicle desire to travel. The invention in all of its details will be fully understood from the following description and claims when the same are read in connection with the drawings accompanying and forming part of this specification in which:

Figure 1, is a front elevation illustrating the signal box and the organized mechanism I employ to designate directions of travel.

Fig. 2 is a side elevation of the device.

Fig. 3 is a detail view of my novel yoke for moving the signal box.

The signal box 1 is of the construction illustrated and in the walls of the box I place slides bearing such legends as "Stop", "Right", "Left", etc.

Within said box 1 an electric bulb 2 is provided on the socket 3. The socket 3 is secured to a threaded conduit 4 through which the wiring passes, it being apparent that the wiring 5 is connected to a suitable source of electric energy (not shown).

The conduit 4 at its outer end is threaded to enter a similarly threaded opening in the support 7, and is secured by a threaded bushing arranged on the support 7. Thus the conduit 4 becomes an axle around which the journal 6 revolves.

Keyed or otherwise movable with the journal 6 is a toothed-wheel 8 that meshes with a toothed-wheel 9 which in turn is loose on the bolt that passes through the support 7 and is secured thereto by the nut 11. As clearly shown, I provide a collar 12 between the support 7 and nut 11 and said collar by preference is threaded to the bolt 10.

By reference to Fig. 1, it will be apparent that the support 7 extends downwardly and has an integral portion 71 formed at right angles to its upstanding portion and secured

to the portion 71 by bolts 14 is a secondary support 13 of U-shaped form.

Secured to and movable in a rotary manner with respect to the support 7 and adjacent the lower end thereof is a shaft 15 and secured on the shaft 15 is a yoke 16 having portions 17, 18 and 19 that surround the shaft 15 and movable independently thereof.

By reference to Fig. 3 it will be seen that a miter gear 20 is fast on the shaft 15 and meshing with the gear 20 is a miter gear 21 made fast to the shaft 23 that passes through the yoke 16 and rests adjacent the shaft 15 and portion 18 of said yoke 16. At its outer end the shaft 23 is provided with a handle 24.

At this point I would distinctly have it understood that the shaft 15 passes through and is movable in the comparatively long upstanding arm of the secondary support 13. However the bolt 10 is secured in permanent manner on the said long arm of the support. I would have it understood that the support 13 may when occasion demands be dispensed with except that portion illustrated to the left of the gear 21 in Fig. 1; the principal purpose of this support 13 being to hold the inner end of the shaft 15 in proper position with respect to portion 71 of support 7.

Between the supports 13 and 7 respectively, the shaft 15 is provided with a toothed-wheel 25 that is keyed and movable with said shaft and between the wheel 25 and support 7 is a collar 26 fast on the shaft 15.

In order to at all times cause the gears 20 and 21 to mesh, I provide in the hubs 27 and 28 respectively of each gear spring washers 29 and 30.

I would distinctly have it understood that the gears 20 and 21 may be of the miter gear or beveled type or of any type compatible with the purpose of my invention.

In the use of the signal, the support 7 is secured on the cowl or in fact at any convenient place on an automobile, so long as the handle 24 is in ready reach of the driver of the vehicle.

When it is desired to show designation or direction by the signal, which under normal conditions shows blank, it is simply necessary to move the handle in a downward or upward direction when the gear 21 will impart rotary motion to shaft 15 and toothed-wheel 25 through gear 20.

The wheel 25 will impart motion to wheel 9 which in turn will rotate wheel 8 and hence journal 6. The journal 6 being secured to signal box 1, naturally another 5 destination signal will be presented to persons in front of or in rear of the vehicle. It is obvious that the operator will be familiar with the signal that is presented to 10 pedestrians or other vehicle occupants and hence will know in what direction to move the handle 24.

It is to be understood that the gears may be decreased or increased in size as well as the wheels and shafts in order to accommodate 15 the same to a larger or smaller signal box. Also when desired the wheel 9 may be dispensed with when occasion demands.

I would have it understood that I do not 20 wish to confine myself to the exact construction and relative arrangement of parts as in the future practice of the invention such changes may be made as fairly fall within the scope of my appended claims.

Having described my invention, what I 25 claim and desire to secure by Letters-Patent is:—

1. In a device for the purpose set forth, the combination of a main support of substantially L-shaped form, a secondary support 30 of substantially V-shaped form secured to the main support, a signal box arranged adjacent the main support near the upper end thereof, a journal that passes through the main support and into the signal box, a toothed wheel mounted on the journal between the box and main support, a short journal passed through the main support and secured at one end to the main support 35 and having its opposite end passed through the V-shaped support and secured to said support, a toothed wheel mounted on the

journal and having its teeth meshed with those of the first named wheel, a shaft arranged below the short journal and passed through the main support and extending 45 through the upstanding arms of the V-shaped support, a beveled gear arranged on the shaft, a yoke secured to and movable about the shaft, a second shaft extending through the yoke and a gear arranged on the inner end of the shaft and having teeth that mesh with those of the beveled gear, and a handle formed integral on one end of the second shaft that extends through the yoke. 50

2. In a device for the purpose set forth the combination of a main support, a secondary support arranged in the main support, a signal box arranged above the secondary support, a journal arranged in the 60 main support and box, a toothed wheel mounted on the journal, a journal arranged below the first-named journal, a toothed wheel secured on the second journal and engaging the first toothed wheel, a shaft passing through the main support and secondary support, a toothed wheel arranged on the shaft directly below and engaging the second toothed wheel and means secured on the shaft for operating the several wheels; said 65 means comprising a yoke, a beveled gear arranged in the yoke and a bevel gear actuatable by the first gear and mounted on the shaft and a handle mounted on the yoke. 70

In testimony whereof I have hereunto set 75 my hand in presence of two subscribing witnesses.

JESSE G. ROSEBOOM.
